UNITED STATES PATENT OFFICE.

CHARLES R. JOHNSON, OF NEW YORK, N. Y., ASSIGNOR TO THE UNION SWITCH AND SIGNAL COMPANY, OF PITTSBURG, PENNSYLVANIA.

RAILWAY-SIGNAL.

SPECIFICATION forming part of Letters Patent No. 310,519, dated January 6, 1885.

Application filed June 25, 1884. (No model.)

To all whom it may concern:

Be it known that I, CHARLES R. JOHNSON, a subject of the Queen of Great Britain, residing in New York, in the county and State of New York, have invented certain new and useful Improvements in Electrical Attachments for Railway Fly-Switches, of which the following is a specification.

My invention relates to a particular method 10 of operating railway-switches for the purpose of sending an engine or a portion of a moving train upon a side track, while the remaining portion of the train, having first been detached therefrom, continues upon the main 15 track, or vice versa.

The object of the invention is to provide, in connection with the means employed for controlling a fly-switch from an interlocking switch tower or cabin, and for insuring that 20 the switch shall be set at the proper times for the siding and for the main track, an organization of apparatus for giving appropriate signals to the operators at the switch-tower, so that they may know whether or not a vehicle 25 is crossing the switch.

The invention consists in organizing a signaling apparatus especially adapted to be employed in connection with a switch-controlling organization in substantially the following 30 manner: A suitable lever and connecting-rods, bell-cranks, and usual appliances are employed for moving the switch from the switch tower or cabin in any well-known manner. In addition to this, a facing-point lock 35 and a detector-bar are employed for the purpose of locking the switch in one position or the other when it has been set, and for preventing the displacement of the same while an engine or a train is passing over it. These 40 devices are all well known, and form no part of the present invention. Two signal-blades or semaphore-arms are employed for indicating to an approaching engine or train the position of the switch with reference to the main 45 track and to the siding, respectively. These two blades are both normally held in a position at right angles to the post, indicating "danger" so long as the switch is not securely locked in connection with either the main 50 track or the siding; but when it is so locked

for either track the corresponding signal-blade will assume a position indicating "safety." The two signal-blades are preferably held in the "danger" position by means of a horizontal movable plate passing beneath the lower ends of two controlling-rods attached to the signals. This plate is provided with two holes, into which the ends of the respective rods are permitted to descend, though not both at the same time, thereby throwing the 55 one blade or the other into position to indicate "safety," accordingly as the switch has been locked in one position or the other. The hereinbefore-mentioned plate is coupled to the system of levers employed for operating 60 the switch from the signal-tower. The rods are normally held up by a special supporting-lever, so that although the plate may be moved into position to allow one or the other of the signal-rods to fall, nevertheless it will 65 stand in its raised position until the locking-levers have been actuated and the special lever moved, thereby allowing the rod to drop through the corresponding hole in the plate. It will be understood, therefore, that a signal 70 cannot be moved into position to indicate "safety" except when the switch is set for either the main track or the siding, by reason of the controlling-plate, and also that by reason of the supporting-lever they are not in practice 75 so moved except when the switch is also locked in the position which it has assumed.

In connection with apparatus of this character, I employ a suitable electric bell or other audible signal for indicating at the signal-tower 80 when a locomotive, car, or train approaches within a given distance—say five feet—of the detector-bar, and this bell continues to ring until the moving vehicle has passed the switch. By means of this audible signal the operator 85 in the tower is informed when he may turn the switch from the main track to the siding, or vice versa.

In the accompanying drawings, which illustrate my invention, Figure 1 is a diagram 90 showing the general plan of the main and side tracks and the levers and attachments employed in connection therewith for operating the switch, the switch-lock, the detector-bar, and the signals. Figs. 2 and 3 are respect- 95 100

ively a front and a side elevation of the signals, showing the organization of the apparatus connected therewith.

Referring to the figures, A represents the incoming railway-track, and A' the main track, continuing, for instance, into the depot. A cross-over is represented at A³, and A⁴ represents the parallel track to which the cross-over leads. The movable switch-rails a a are connected, in the usual manner, with a bridle rod or bar, B', which in turn is connected, through a suitable system of cranks, D', and connecting-rods d', with a switch-lever, C. The switch-lever C is located at any convenient point, 15 preferably in the interlocking-switch tower J, from which the several switches employed in the vicinity of a given locality are operated. By moving the lever C in one direction or the other, the switch-rails a will be moved laterally, so as to connect the rails of the incoming track A' either with the main track or with the siding, in a manner well understood.

A safety or detector bar, E, and facing-point lock F, both of which are of well-known construction and need not here be particularly described, are connected, through a system of cranks, D², and connecting-rod d², with a locking-lever, C², located near the switch-lever C' in the switch-tower. The method of operating these two levers is substantially that usually employed in operating switches and their locks from a distant point.

At a suitable distance—say fifty feet—from the switch in the direction from which the trains approach there are placed two signal-blades or semaphore-arms, G' and G². The blades are pivoted upon any suitable support, H, and their indicating positions are controlled by means of suitable rods, g' and g², respectively. The lower ends of the rods g' and g² terminate just above a horizontal movable slide-plate, K, in which are formed two holes, k' and k², respectively designed to receive the ends of the rods g' and g², accordingly as it is desired to move one or the other of the signal-blades into a position indicating "safety."

The blades G' and G² are respectively designed to indicate the position of the switch-rails with reference to the main track A' and side track A⁴. Normally both blades extend horizontally from the side of the support H, and the one or the other is designed to be dropped to indicate "safety," accordingly as the switch is placed in connection with the main or with the side track and locked. The slide-plate K is connected through a system of rods and cranks, f', with the system of cranks D' and rods d', controlled by the switch-lever C', and it is moved so that the hole k' will be beneath the rod g' when the switch is in connection with the main track A', and likewise so that the hole k² will be beneath the rod g² when the switch is in connection with the siding A⁴. A special balance-lever, h', is, however, applied to the signal-blades G' and G², and this lever is designed to prevent either rod from falling into the cor-

responding hole, except when the locking-lever C² is in position to lock the switch in one or the other of its two positions. For this purpose the balance-lever is coupled with the system of cranks D² and rods d², which are connected with the locking-lever C², and when the lever C² is thrown into position to lock the switch the balance-lever is actuated. 75 When the cranks D² and rods d² are actuated, the rods g' and g² will be relieved of the weight of the lever h', and one or the other rod will fall through the corresponding hole, thus dropping the signal-blade attached thereto. Only one of the blades, however, can be dropped in this manner at a time, for the reason that only one of the holes k' or k² will be beneath the corresponding rod. 80

For the purpose of indicating to the operator at the switch-tower when an engine or a train is passing the switch, it is desirable to employ some form of automatic signal device. To illustrate the application of such a device I have shown an electric bell, M, placed in 9c the switch-tower. A battery, o, is employed for actuating the bell, and the circuit-connections of this battery are designed to be completed by the train or by any moving vehicle during the time which it occupies in passing 95 the switch. For this purpose the circuit may conveniently be arranged in the manner indicated in Fig. 1—that is to say, a conductor, 1, may lead from one pole of the battery o to one line of rails, a', while the other pole is in 100 like manner connected by means of a conductor, 2, through the coils of an electro-magnet, n, which actuates the continuously ringing or vibrating bell M, and from thence, by means of a conductor, 3, with an insulated track-section, a², of well-known construction. The connections of this circuit, it will be evident, will be normally incomplete; but when a locomotive, car, or train is passing the switch, so long as any portion of it is traversing the 110 insulated rail-section, the circuit is completed through the wheels and axles of the trucks, and the bell will therefore continue to ring until the vehicle has entirely passed the switch. 115

The method of operation of this organization of switches and signals is as follows: When, for instance, a train is proceeding in the direction pointed out by the arrow, and it is desired to send the locomotive upon the siding A⁴, and cause the train itself to continue along the main track A', then the locking-lever C² is first thrown over, thereby causing both signal-blades to be thrown into position to indicate "danger," at the same time unlocking the 120 switch by withdrawing the bolt F' from the locking-plate in a manner well understood. The switch-lever C' is then thrown over, and the switch-rails thereby place the track in connection with the siding A⁴. The same movement of the lever C' causes the plate K to be moved in such position that the hole k² is beneath the rod g². This rod, however, does not fall instantly by reason of the action of the 125 130

balance-lever h' . The locking-lever C' is then thrown back, thereby causing the detector-bar to be thrown over and the switch to be locked in the usual manner. The same movement of 5 the locking-lever C' actuates the balancing lever h' , thereby permitting the rod g^2 to fall into the hole k^2 and the blade G^2 to drop. This indicates to the engine-man upon the approaching train that the switch is set and 10 locked for the siding. When the engine has approached within a certain distance from the switch, the bell at M is automatically actuated, and the operator at the tower is thus notified that a vehicle is passing the switch. The 15 movement the bell ceases to ring, the operator understands that the passing vehicle is clear of the switch, and he immediately throws over the locking-lever C' , thereby causing the blade G^2 to be again thrown into position to indicate 20 "danger." He then moves the switch-lever C' back, so that the switch is set for the main track A' , and then by means of a lever, C' , locks the switch in that position. The movement of the locking-lever C' relieves the 25 rods g' and g^2 of their balance-lever h' , and permits the rod g' to fall into the hole k' , which has been brought beneath the same by the movement of the lever C' . The blade C is thus brought into position to indicate to the 30 train-man upon the train which has been detached from the engine that the switch is locked for the main track A' . The train, upon approaching the switch, causes the bell M to be again actuated, in the manner described with reference 35 to the engine, until the train itself has passed the switch. By means of this organization of apparatus the necessity of placing an

operator immediately at the switch is avoided, and the entire operation of controlling the switch may be performed with perfect safety 40 and convenience at the switch-tower, where the several other switch-operating levers are located. Moreover, the possibility of any error in operating the switch for controlling the train movements is prevented, and signals are given 45 respectively to the engine-man and brakeman in charge of the detached train.

I claim as my invention—

The combination, substantially as herein-before set forth, with a main track and a siding, of movable switch-rails and mechanism for operating the same, a switch-lock and mechanism for operating said lock, signal devices for indicating the two positions of the switch-rails, a device for permitting one or 50 the other of said signals to be operated, which is controlled by said switch-operating mechanism, means, substantially such as described, controlled by said locking mechanism, for preventing one or the other of said signal-blades 55 from being operated except when said switches are locked in one position or the other, an electric signal-bell, and means, substantially such as described, for completing an electric circuit through the same while a train or engine is passing along said switch-rails.

In testimony whereof I have hereunto subscribed my name this 21st day of June, A. D. 1884.

CHARLES R. JOHNSON.
